AUXILIARY WIPING MECHANISMS

Ernest Harry Simms and John Richard Ainsworth, Leicester, England, assignors to United Shoe Machinery Corporation, Flemington, N. J., a corporation of New Jersey

Application March 5, 1953, Serial No. 340,602

Claims priority, application Great Britain
April 8, 1952

7 Claims. (Cl. 12—55)

1
This invention relates to auxiliary attachments for wiping a folded margin tightly over the body of the work and it is herein illustrated as embodied in a machine of the type shown in United States Letters Patent No. 2,301,202, granted November 10, 1942, upon an application of Paul H. Dixon.

Folding machines for use in folding the margins of shoe uppers have commonly been constructed so that the turning up of the work margin is accomplished by the use of an oscillatory finger movable nearly heightwise to press the margin against the side of a depending creaser foot. This upturned work is then pressed down by a hammer and gripped against an anvil. The feeding of the work is accomplished by a swinging of the hammer and anvil together. It has long been recognized, however, that there is a possibility that the upturned margin will draw back between the time when it leaves the folding finger and before it is gripped by the hammer. The fact remains, however, that a tight fold is the mark of good work and various attachments have been provided for such excellence.

It is an object of the invention to provide an improved wiper mechanism which will be effective to make a tight fold.

In some forms of women's shoes, it is not uncommon to have two or more straps which extend across the top of the foot and between which there is a rather narrow throat. In order to work effectively upon work of this type it is essential that there shall be no machine parts which will interfere with the swinging of the work around the throat.

One feature of the invention, therefore, is to provide a wiper mechanism which is hung upon the machine at a point above the work. In the illustrated machine this suspension of the wiper involves a swingable member having a ball-shaped end upon which the wiper itself is pivoted.

The actuation of the wiper is effected by a link connection to the hammer and, in accordance with another feature of the invention, the arrangement is such that the wiping movement takes place during movement of the hammer toward the anvil, thereby to tighten a portion of the work before the work is gripped between the hammer and anvil. With this mechanism, also, the wiper is carried through a four-motion path in which it wipes, is raised, moves to a forward position and then is carried downward to wipe again as the hammer moves forward to its initial position.

2
Still another feature of the invention will be found in an arrangement such that a lifting of the creaser foot to admit a new piece of work is accompanied by a lifting of the wiper.

This and other features of the invention will best be understood from a consideration of the following specification taken in connection with the accompanying drawings in which:

Fig. 1 is a rear elevation of the head of the folding machine showing the hammer in raised position;

Fig. 2 is a fragmentary view of parts of the same portion of the machine but viewed from the other side, i. e., the front of the machine, and showing the hammer in engagement with the work just as the wiper member completes its traverse of the folded edge; and

Fig. 3 is a vertical section on the line III—III of Fig. 2.

The machine shown in the drawings comprises a lower work-supporting arm 10 in which there is mounted an oscillatory hollow shaft 12 carrying an anvil 14 and a hammer 16. Except for the shape of the hammer these parts are like those found in the Dixon Patent No. 2,301,202 and operate in the same way. Similarly too, there is provided a folding finger 18 carried by an arm 20 which is pivoted at 22. The machine is also provided with an overhanging arm (not shown) on which there is mounted a stationary plate 24. The lower end 26 of this plate carries a pivot pin 28 which supports a finger lever 30 having at its outer end a link 32 connected to the upper end of a slidably mounted creaser foot 34, and when a piece of work is to be presented to the machine, this creaser foot is lifted by a depression of the left end of the lever 30, as viewed in Fig. 1 as disclosed more fully in the Dixon patent. The wiper mechanism includes a thin plate 40 having a rounded corner 42 (Fig. 2) and the lower end of this plate is swung across the folded margin of the work to wipe it tightly. In the drawings, the work is shown as comprising a portion of an upper 44 having attached to it a French binding 46 which is shown in Fig. 1 as standing up between the folding finger 18 and the side of the creaser foot 34 and is shown in Fig. 2 as wiped over upon the work and gripped against the anvil 14 by the hammer 16.

In order to provide for the support of the wiper 40 from a point on the machine above the work, the hand lever 30 has mounted thereon a bracket 58 which is attached to the lever by means of screws 52 and which has an overhanging end 54 bored for the reception of a pivot pin 56 extend-

50
45
55

ing laterally from a housing 58. This pivot pin is provided with a retaining collar 60 and the housing is bored for the reception of a plunger 62, having on its lower end a ball 64. The plunger is slidable in the housing 58 as far as is permitted by a collar 66 and is normally held down by a spring 68 inside the housing and tensioned between a shoulder therein and an enlarged portion 10 of the plunger.

The upper end of a split carrier link 72 is provided with a ball socket surrounding the ball 64 of the plunger 62. The lower end of the carrier 72 is bifurcated to receive one end of a link 74 connected to it by means of a transverse bolt 76. The other end of the link 74 is joined to a forked upper portion 78 of the hammer 16 and is attached thereto by a pivot pin 80. The wiper blade 40 is mounted on the side of this carrier link 72 by means of a screw 82 and the head of the bolt 76. The length of the wiping member is preferably such that the lower edge projects slightly below the face of the hammer when the hammer is in contact with the anvil and no work is in the machine. At that time also the ball-plunger 62 and the carrier link 72 are substantially aligned (when viewed from the end of the machine), the spring 68 allowing the wiping member to yield upwardly. The position of the lower edge of the wiper can be regulated by adjusting the heightwise position of the bracket 50 on the lever 36. The left hand lower corner 42 of the wiping member 40, as seen in Fig. 2, is rounded to avoid damage to the binding strip, and the binding engaging end of the wiping member may be serrated if desired.

It will thus be understood that the arrangement is such that movement of the hammer downwardly and to the left, as viewed in Fig. 2, as it closes upon the work, moves the actuating link 74 to cause the carrier link 72 and the wiping member 40 fixed thereto to swing in a clockwise direction about the ball at the end of the plunger 62. This movement effects a wiping of the binding substantially at right angles to the direction of the work feed, the wiping member having moved off the binding (or substantially so) by the time the hammer presses upon the work. As the hammer and anvil swing rearwardly to feed the work, the carrier link 72 is canted rearwardly breaking its alignment with the plunger 62 (as shown in Fig. 3) by swinging the plunger 62 rearwardly owing to the pivoting of housing 58 on its pivot pin 56 in the bearing arm 54. This "foreshortening" of the linkage causes the wiping member 40 (Fig. 3) to be lifted from the work, and the hammer, as it recedes upwardly, again draws back the wiping member, then out of engagement with the work, away from a position over the margin of the work in readiness for the next wiping movement.

The wiping member thus has a four-way motion, namely: (a) a movement from right to left as seen in Fig. 2 (i. e. substantially at right angles to the direction of the work feed) in engagement with the work (thereby tightening the binding around the edge of the work, as the hammer is moving down on to the work to grip it), (b) a rearward and upward movement to the position shown in Fig. 3 (out of engagement with the work) as the hammer feeds the work in cooperation with the anvil, (c) a left to right (Fig. 2) return movement as the hammer is raised and (d) a final movement to the front and then downward as the hammer moves forward to its initial position.

It will be clear that in the arrangement herein described there is no upwardly projecting part which is likely to obstruct the passage of an upper past the folding, wiping and pressing instrumentalities of the illustrative machine even on narrow throated work.

In the operation of the machine, after a workpiece, for example a shoe upper 44, has been presented to the machine and the treadle (not shown) as described in the aforementioned Dixon patent, is operated to cause rotation of the drive shaft (not shown) the binding is turned up by the folding finger 18 against the adjacent surface of the creaser foot 34 through which adhesive is supplied and the hammer then at the forward end of its movement moves downward towards the anvil 14 to press the folded portion of the binding against the workpiece. As soon as this downward movement of the hammer commences, the wiping member commences to move across the binding at right angles to the direction of work feed and wipes the binding, under spring pressure, inwardly of the workpiece. The lateral movement of the wiping member is completed (as shown in Fig. 2) and the wiping member has traversed the full width of the turned-over binding by the time that the hammer has completed its downward movement. The hammer then moves rearwardly, still gripping the work against the anvil, to feed the work, and the wiping member is raised from the workpiece (see Fig. 3). The hammer is then raised returning the wiping finger, now out of engagement with the work, to the right beyond the edge of the workpiece, and finally moves forward, causing the linkage of the wiping mechanism to straighten and bring the wiping member into a position shown in Fig. 1 to repeat the wiping operation on a successive portion of the workpiece.

It will be understood that as the wiping operation of the illustrative machine is performed while the hammer is out of engagement with the work the effect of the wipe is likely to be both extensive and efficient.

Having thus described our invention, what we claim as new and desire to secure by Letters Patent of the United States is:

1. In a progressive folding machine, a folding mechanism, a work-gripping and feeding mechanism movable toward and away from the folding mechanism, a wiping member swingably supported on the machine from a point above the work, and a connection between part of said work-gripping mechanism and said wiping member arranged to swing it across the margin to be folded prior to the gripping of the work to feed it.

2. In a progressive folding machine, a hammer and anvil movable toward each other to grip the margin of the work and swingable forward and back to feed the work, a hanging wiping member swingable across the margin of the work just ahead of the hammer, and a connection between the hammer and the wiping member to move the latter across the margin of the folded work.

3. In a progressive folding machine, work-feeding mechanism comprising a hammer and anvil, margin-folding mechanism, a wiping member swingably mounted on the machine at a point above the said mechanisms, the lower end of said swinging member being positioned between the folding mechanism and the work feeding mechanism, and a connection to one of said mechanisms to cause the wiping member to move

across the margin of the work just after it has been folded.

4. In a French-binding folding machine, means for turning up the binding, a swingably mounted wiper member, a connection to an overhanging part of the machine to pivotally support said wiping member for movement from front to back and laterally, a hammer-and-anvil feed mechanism, and a link between said hammer and an intermediate part of said wiping member to swing it across the binding after the latter has been turned up and before it is gripped by the hammer.

5. A progressive folding machine provided with a frame, means carried by said frame for pivotally supporting a swingably mounted depending wiper member, means for turning up a margin of the work located ahead of the wiping member, means for feeding and pressing the work located beyond the wiping member, means for swinging the wiper member to move across the work just ahead of the gripping mechanism, the support for said wiping member including a ball and socket joint permitting movement of the wiping member with respect to the work along a four-motion path.

6. In a progressive folding machine, a frame 25 a member swingable about an axis extending

transversely to the margin of the work, means carried by the frame for pivotally supporting said member, a ball yieldably carried thereby, a wiper member swingable on the ball, and a hammer-and-anvil feeding mechanism, said hammer having a slotted portion carrying a link which is pivotally attached to said wiper member.

7. A progressive folding machine provided with a frame, a hammer-and-anvil feeding mechanism for pressing the work and carrying it forward, folding mechanism for turning up the margin of the work, said folding mechanism including a creaser foot slidably mounted on the frame, a finger lever on said frame connected to said creaser foot to raise it for the insertion of a new piece of work, a wiper member swingably supported upon said finger lever, and a link connection between the wiper member and the hammer of the feeding mechanism whereby the raising of the creaser foot by actuation of the finger lever is also effective to raise the wiper away from the work.
